[57] **CLAIM**

The ornamental design for a golf club head, as shown and described.

DESCRIPTION

FIG. 1 is a front elevational view of a golf club head showing my new design;

FIG. 2 is a bottom plan view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a front elevational view of a second embodiment of the club head as disclosed in FIG. 1;

FIG. 8 is a bottom plan view of FIG. 7;

FIG. 9 is a rear elevational view of FIG. 7;

FIG. 10 is a top plan view of FIG. 7;

FIG. 11 is a left side elevational view of FIG. 7;

FIG. 12 is a right side elevational view of FIG. 7;

FIG. 13 is a front elevational view of a third embodiment of the club head as disclosed in FIG. 1;
FIG. 14 is a right side elevational view of FIG. 13;
FIG. 15 is a top plan view of FIG. 13;
FIG. 16 is a rear elevational view of FIG. 13;
FIG. 17 is a bottom plan view of FIG. 13;
FIG. 18 is a left side elevational view of FIG. 13;
FIG. 19 is a front elevational view of a fourth embodiment of the club head as disclosed in FIG. 1;

FIG. 20 is a left side elevational view of FIG. 19;
FIG. 21 is a right side elevational view of FIG. 19;
FIG. 22 is a top plan view of FIG. 19;
FIG. 23 is a bottom plan view of FIG. 19; and,
FIG. 24 is a rear elevational view of FIG. 19.
